UNITED STATES PATENT OFFICE.

ALEXANDER B. BURNS AND JAMES T. KETCHUM, OF GREEN BAY,
WISCONSIN.

STEAM-BOILER.

SPECIFICATION forming part of Letters Patent No. 593,921, dated November 16, 1897.

Application filed March 17, 1897. Serial No. 627,951. (No model.)

To all whom it may concern:

Be it known that we, ALEXANDER B. BURNS and JAMES T. KETCHUM, citizens of the United States, residing at Green Bay, in the county of Brown and State of Wisconsin; have invented a new and useful Steam-Boiler, of which the following is a specification.

This invention relates to steam-boilers; and it has for its object to effect certain new and useful improvements in boilers of that character that are designed for either power, steam, or hot-water heating.

To this end the main and primary object of the invention is to so construct a boiler of this type whereby all of the heating-surfaces will be exposed to the direct contact of the fire and hot gases, thereby insuring economy of fuel, and also providing a construction in which every part of the heating-surfaces may be readily accessible and easily cleaned.

With these and other objects in view, which will readily appear as the nature of the invention is better understood, the same consists in the novel construction, combination, and arrangement of parts hereinafter more fully described, illustrated, and claimed.

In the drawings, Figure 1 is a perspective view of a boiler constructed in accordance with this invention. Fig. 2 is a vertical longitudinal sectional view thereof. Fig. 3 is a top plan view. Fig. 4 is a front end view of the boiler.

Referring to the accompanying drawings, 1 designates a suitable boiler-furnace having in the front part thereof the usual fire-grate 2, above which is arranged the fire-box 3, and suitably supported within the furnace 1 is the boiler 4, constructed in accordance with this invention. The boiler 4 essentially comprises the separate cylindrical shell-sections 5 and 6, which are of different diameters and eccentrically arranged with relation to each other, the front shell-section 6 being smaller than the rear shell-section 5. The separate large and small sections 5 and 6 of the boiler, while eccentrically arranged with respect to their longitudinal alinement, are disposed so that the upper side of the front smaller shell-section 6 is substantially in a line with the upper side of the rear larger shell-section 5,

with the lower portion of the rear large section 5 projecting materially below the lower side of the front smaller section 6, as clearly illustrated in Figs. 1, 2, and 4 of the drawings.

The two sections 5 and 6 of the boiler are in direct communication with each other and are joined or united together by an intermediate crescent-shaped head-plate 7, which is securely riveted to the adjacent end edges of the said shell-sections 5 and 6, and the boiler-body is completed by the front and rear head-plates 8 and 9, respectively fitted to the front end of the shell-section 6 and to the rear end of the rear shell-section 5. The several head-plates 7, 8, and 9 form the flue-sheets of the boiler, and a series of long return-flues 10 extend the entire length of the boiler 4 and are fitted at their opposite ends, respectively, in the end head-plates or flue-sheets 8 and 9, and a series of shorter fire-flues 11 extend only the length of the rear shell-section 5 and are fitted at their ends, respectively, in the rear head-plate 9 and the intermediate crescent-shaped head-plate 7, which forms a connection between the adjacent ends of the separate sections of the boiler.

A smoke-box extension 12 is fitted to the rear end of the boiler and incloses a space beyond the rear ends of all of the flues 10 and 11 to provide for directing the fire and hot gases which escape out of the rear ends of the flues 11 into the rear ends of the return-flues 10, as will be readily understood by those skilled in the art.

The boiler-body being constructed as described, with both shells thereof on a circle, the strain is equal and no stay-bolts are required, and at this point it is to be noted that the front shell-section 6 of the boiler extends the full length of the fire-box 3 and forms a crown-sheet therefor, whereby the entire lower side of the front small section of the boiler will be subjected to the direct action of the fire and hot gases, and the lower front end portion of the rear section 5, formed by the intermediate head-plate 7, is disposed immediately above the grate-line at the rear side of the fire-box and forms the rear wall of said fire-box, so that all of the fire and hot gases from the fire-box are compelled to pass

directly into the front ends of the short fire-flues 11, and practically no heat whatever is lost, but passes directly inside of the boiler.

In connection with the front smaller shell-

- 5 section 6 of the boiler is employed a pair of header-pipes 13, arranged, respectively, at opposite sides of the grate 2, immediately above the grate-line, and said opposite header-pipes 13 have coupled thereto the lower ends 10 of a vertical series of circulating-pipes 14, arranged in separate series at opposite sides of the fire-box and forming the side walls of the said fire-box. The series of vertical circulating pipes or tubes 14 at one side of the fire-box extend upward from their point of connection with one of the pipes 13 and are connected with one side of the shell-section 6, as at 15, at a point about on a line with the top row of flues 10, while the circulating pipes or 20 tubes 14 at the opposite side of the fire-box are connected at their upper ends, as at 16, with one side of the shell-section 6 at a point about on a line with the lower row of flues 10, whereby a continuous circulation of water 25 can be maintained within the boiler and through the opposite sets or series of pipes or tubes 14, it being noted that said opposite sets of pipes or tubes 14 are directly adjacent to the fire-surface and are naturally subjected to the direct influence of heat therefrom.

The opposite header-pipes 13 for the opposite sets of circulating pipes or tubes 14 are connected at their rear ends with a transverse bridge-wall pipe 17, which is arranged at the rear side of the grate 2, directly under the front lower side of the shell-section 5, to form the bridge-wall for the fire box or chamber, while at the same time to assist in heating up the water circulated therein, and the said bridge-wall pipe 17 is suitably connected at its opposite ends with a return-piping frame 18, having a connection 19 with the lower side of the large shell-section 5 and feed-pipe 45 connections 20, as plainly illustrated in the drawings.

The herein-described construction of boiler, in combination with the particular piping described, provides a large heating area exposed 50 directly to the fire and therefore necessarily provides for a uniform and rapid heating of the water within the boiler and the pipes connected therewith, thereby rendering the boiler especially available for power, steam, or hot-water heating.

The smoke-box extension 12 may be provided at one side with double doors 13, and any changes in the form, proportion, and the

minor details of construction may be resorted to without departing from the principle or 60 sacrificing any of the advantages of this invention.

Having thus described the invention, what is claimed, and desired to be secured by Letters Patent, is—

65 1. In a boiler, the combination with a furnace and the fire-grate therein; of the boiler proper essentially comprising separate shell-sections of different diameter and eccentrically disposed, and the fire-flues extending the 70 entire length of the boiler and also through the lower part of the larger section, the smaller section of the boiler forming the crown-sheet for the fire-box above the grate, and the lower front end portion of the large section forming 75 the rear wall of the fire-box immediately above the grate-line, a transverse bridge-wall pipe arranged directly under the front lower side of the larger shell-section, and circulating-pipe connections with said transverse bridge-wall pipe, substantially as set forth.

80 2. The combination with a boiler-furnace and the fire-grate therein; of a boiler essentially comprising separate eccentrically-disposed shell-sections of different diameter, and 85 the fire-flues extending through the entire length of the boiler, and also through the lower part of the large section, the smaller section of the boiler lying above the fire-grate, and the lower front end portion of the larger 90 section being disposed at the rear side of the grate immediately above the grate-line, a transverse bridge-wall pipe arranged under the front lower side of the larger shell-section, opposite header-pipes connected with the 95 bridge-wall pipe and arranged at opposite sides of the grate, a return-piping frame connected with the bridge-wall pipe and with the lower side of the large shell-section, and opposite sets or series of vertical circulating-pipes connected at their lower ends with said 100 header-pipes and at their upper ends to opposite sides of the smaller shell-section, respectively at points about on a line with the top and bottom rows of flues in such section, substantially as set forth.

105 In testimony that we claim the foregoing as our own we have hereto affixed our signatures in the presence of witnesses.

ALEXANDER B. BURNS.
JAMES T. KETCHUM.
